UNITED STATES PATENT OFFICE.

OSCAR E. A. WIESSNER, OF NEW YORK, N. Y.

DESIGN FOR AN END PIECE FOR BEDSTEADS.

SPECIFICATION forming part of Design No. 30,017, dated January 17, 1899.

Application filed June 18, 1898. Serial No. 683,863. Term of patent 3½ years.

To all whom it may concern:

Be it known that I, OSCAR E. A. WIESSNER, a citizen of the United States, and a resident of New York, (Brooklyn,) in the county of 5 Kings and State of New York, have invented and produced a Design for an End Piece for Bedsteads, of which the following is a specification, reference being had to the accompanying drawing, forming a part thereof, and 10 wherein the end piece of a bedstead involving my design is shown in elevation.

The leading or material features of the design are to be found within the rectangular space defined by the letters A B C D and con- 15 stitute what may be termed an "urn-shaped" figure, the outline thereof being formed by the curved rods 9 10 11 12.

The end piece of the bedstead embracing the essential features of the design has the 20 usual side posts, joined by the horizontal rails 5 and 6 and the bottom rail 20. It also has the vertical rods 7 and 8, paralleled with said posts, and a supplemental horizontal rail 21, located below rail 6.

25 The rods 11 and 12 have a scroll formed thereon at their adjacent ends, and from said scroll there extend to the side posts short horizontal rails 13 and 14. There are also

short rods 18 and 19 extending from the intersection of the rods 7 and 8 with the rails 6 30 to the curved rods 9 and 10, which form the lateral lines of the urn-shaped figure.

Extending vertically through the middle of the urn from the rail 5 to the rail 21 is a vertical rod 15. This rod, together with rods 16 35 and 17, forms what may be considered as divisional lines in the surface of the urn-shaped figure.

At the intersection of the several rods, rails, and posts below the top rail 5 there are 40 flowers, as illustrated.

The rail 5 and the mounts at the upper ends of the posts and the smaller mounts at the upper ends of the rods 7, 8, and 15 are of brass or bronze, and the flowers 22 are faced 45 with brass or bronze rosettes.

I claim as my invention—

The design for an end piece of a bedstead, substantially as shown and described.

Signed at Brooklyn, in the county of Kings 50 and State of New York, this 16th day of June, A. D. 1898.

OSCAR E. A. WIESSNER.
